UNITED STATES PATENT OFFICE.

RUDOLPH HENRIK PAUS, OF SHIPLEY, ENGLAND.

FLUSHING-CISTERN.

1,243,340.

Specification of Letters Patent. Patented Oct. 16, 1917.

Application filed May 24, 1915. Serial No. 30,185.

To all whom it may concern:

Be it known that I, RUDOLPH HENRIK PAUS, a subject of the King of England, and residing at Shipley, in Yorkshire and the 5 Kingdom of England, have invented certain new and useful Improvements in Flushing-Cisterns, of which the following is a specification.

This invention relates to flushing cisterns 10 of the siphon type for water closets, urinals, and other appliances and has for its chief object to produce a cistern which will be absolutely silent in its action.

Various devices have been proposed with 15 a view to effecting this object such for example as one or more pipes or passages of small bore which enter the siphon at or about its highest level and extend to within a short distance above the level of the 20 siphon inlet aperture. Apparatus of this kind while effecting great improvements over the ordinary siphon cistern is not absolutely silent as there is still a certain amount of noise produced by the inrush of 25 air through the small pipe or pipes as the water level in the cistern arrives at and falls below the end or ends of such pipes.

According to this invention in order to 30 eliminate this last mentioned objection an air pipe is employed which extends above the highest water level and opens to the atmosphere directly, or through the intervention of a silencer or if desired such a pipe entering the short leg of the siphon or terminating in an open chamber and occupying 35 a position slightly above the lower end or ends of the aforesaid silencing pipes, the arrangement being such that as the water level in the cistern falls during a flushing operation it falls simultaneously in the air pipe and chamber and opens such chamber to the atmosphere before the level of the water in the chamber reaches the ends of the small 40 silencing pipe or pipes therein and any bubbling or hissing that may be caused by the water level uncovering the lower end or ends of the last mentioned pipe or pipes is effectually silenced by the inclosing wall of the chamber and the considerable length of 45 the pipe which extends above the highest water level and terminates as already mentioned in a silencer if so desired.

In order that the said invention may be 50 clearly understood and readily carried into

effect the same is described by way of example with reference to the accompanying diagrammatic drawings, in which:—

Figure 1 is a longitudinal section of a flushing cistern showing the invention applied to a siphon having a vertical siphon 60 operating cylinder.

Fig. 2 is a similar view showing the invention applied to a siphon having a horizontal siphon operating cylinder and the air pipe leading to the atmosphere through 65 the intervention of a silencer.

Fig. 3 shows the invention applied to a bell siphon.

Fig. 4 is a similar view showing the invention applied to a type of valveless bell 70 siphon, and

Fig. 5 shows a modification in which the air pipe enters the short leg of the siphon.

A indicates the siphon, B, B', B² the silencing pipes, C the air pipe, D the 75 silencer, E the highest water level and F the lowest water level.

In the examples shown in Figs. 1 and 2 the pipes, B, B', B² are similar to those described in my prior British specification of 80 Letters Patent No. 1352/13 with the exception that the lower end of such pipes projects into a casing or chamber c with the lower ends occupying a position that is somewhat below the lower end of the pipe 85 C. The upper end of this pipe extends above the highest water level and may open directly to the atmosphere as shown in Fig. 1 or if desired may be fitted with a silencer 90 D; Fig. 2. In the example shown, this silencer comprises a casting containing two perforated pipes d d' separated from one another by a diaphragm d² which is formed with perforations outside the pipes d d' and causes the entering air to travel in the direction indicated by the arrows. This silencer is shown by way of example only and any other appropriate type may be used. The 95 pipes B, B', B² are formed at their upper portions with small apertures or pin holes 100 b and any suitable means can be employed for operating the siphon such for example as a piston mounted in a cylinder which may be vertical as shown at a in Fig. 1 or horizontal as shown at a' in Fig. 2, water 105 entering through the bottom of the cylinder a or by way of an aperture or valve a² in the cylinder a'. The chamber or casing c can

be made of any shape to suit the design of the cistern and if desired can be cast in a piece with the siphon operating cylinder *a* or *a'*, the bottom or lower part of the chamber *c* being open to allow the water to flow freely in and out and always be at the same level as the water in the cistern. In the example shown in Figs. 3 and 4, *A'* indicates a bell that constitutes the short leg of the siphon and also serves as an operating cylinder. One of the silencing pipes *B* opens into the top of such bell and extends downwardly outside the chamber or casing *c* which is open at *c'* and may be formed in a piece with the bell. Projecting from the top of such casing is the air pipe *C* which may be constructed and arranged to operate in the manner previously described. In these examples only one of the silencing pipes *B* is shown but if desired two or more of such pipes may be used as shown with reference to Figs. 1 and 2.

Fig. 5 shows an example in which the supplementary chamber or casing *c* is dispensed with, the air pipe *C* entering the short leg of the siphon at *c''* just above the siphon inlet aperture *c'*. In this case the lower end of the air pipe is open and terminates at or about the level of the siphon inlet aperture.

When the silencing pipes are used in connection with a supplementary chamber *c* the small pin holes *b* may be dispensed with.

I claim:

1. In a flushing-cistern, a siphon, a pipe connected at one end to said siphon and having an opening in its other end exposed to the rising and falling action of the body of the flushing-liquid but above the level of the influx of the siphon, and a pipe open at one end to the atmosphere for supplying air to the first pipe through said opening when the latter is uncovered during flushing.

2. In a flushing-cistern, a siphon, a pipe connected thereto, said pipe having an ever-open air-inlet aperture above the normal water-level and having an opening in its other end above the level of the influx of the siphon, and a pipe open at one end to the atmosphere for supplying air to the first pipe through said opening when the latter is uncovered during flushing.

3. In a flushing-cistern, a siphon, a pipe connected thereto, said pipe having an ever-open air-inlet aperture above the normal water-level and having an opening in its other end exposed to the rising and falling action of the body of the flushing-liquid but above the level of the influx of the siphon, and a pipe open at one end to the atmosphere for supplying air to the first pipe through said opening when the latter is uncovered during flushing.

4. In a flushing-cistern, a siphon, a pipe connected at one end to said siphon, and having an opening in its other end exposed

to the rising and falling action of the body of the flushing liquid but above the level of the influx of the siphon, and a pipe having one end open to the atmosphere above the normal water-level and its other end positioned to allow air to pass into the first pipe through said opening when the latter is uncovered during flushing.

5. In a flushing-cistern, a siphon, a pipe connected at one end to said siphon and having an opening in its other end above the level of the influx of the siphon, a pipe open at one end to the atmosphere for supplying air to the first pipe through said opening when the latter is uncovered during flushing, and a silencing-device at the inlet-end of the air-supplying pipe.

6. In a flushing-cistern, a siphon, a plurality of pipes connected at their upper ends to said siphon and having openings in their lower ends above the level of the influx of said siphon, each of said pipes having a bore of relatively small diameter and having an ever-open air-inlet above the normal water-level, and a pipe open at one end to the atmosphere for supplying air to said pipes through said openings when the latter are uncovered during flushing.

7. In a flushing-cistern, a siphon, a plurality of pipes connected at their upper ends to said siphon and having openings in their lower ends exposed to the rising and falling action of the body of the flushing-liquid, but above the level of the influx of the siphon, each of said pipes having a bore of relatively small diameter and having an ever-open air-inlet above the normal water-level, and a pipe having one end open to the atmosphere above the normal water-level and its other end positioned to allow air to pass into said pipes through said openings when the latter are uncovered during flushing.

8. In a flushing-cistern, a siphon, a pipe connected at one end to said siphon and having an opening in its other end exposed to the rising and falling action of the body of the flushing-liquid but above the level of the influx of the siphon, a chamber in communication with the cistern and receiving the lower end of said pipe, and a pipe open at one end to the atmosphere and connected at its other end to said chamber for supplying air thereto and thereby to the first pipe through said opening when the latter is uncovered during flushing.

9. In a flushing-cistern, a siphon, a plurality of pipes connected at their upper ends to said siphon and having openings in their lower ends exposed to the rising and falling action of the body of the flushing liquid but above the level of the influx of said siphon, a chamber in communication with the cistern and receiving the lower ends of said pipes, and a pipe open at one end to the atmosphere and connected at its other end to said

chamber for supplying air thereto and thereby to said pipes through said openings when the latter are uncovered during flushing.

10. In a flushing-cistern, a siphon, a plurality of pipes connected at their upper ends to said siphon and having openings in their lower ends above the level of the influx of said siphon, each of said pipes having a bore of relatively small diameter and having an ever-open air-inlet above the normal water-level, a chamber in communication with the cistern and receiving the lower ends of said pipes, and a pipe open at one end to the atmosphere and connected at its other end to said chamber for supplying air thereto and thereby to said pipes through said openings when the latter are uncovered during flushing.

11. In a flushing-cistern, a siphon, a pipe connected at one end to said siphon, and having an opening in its other end exposed to the rising and falling action of the body of the flushing-liquid but above the level of the influx of said siphon, a chamber in communication with the cistern and receiving the lower end of said pipe, and a pipe open at one end to the atmosphere and connected at its other end to said chamber above said opening for supplying air to the chamber and thereby to the first pipe through said opening when the latter is uncovered during flushing.

12. In a flushing-cistern, a siphon, a plurality of pipes connected at their upper ends to said siphon and having openings in their lower ends exposed to the rising and falling action of the body of the flushing-liquid but above the level of the influx of said siphon, a chamber in communication with the cistern and receiving the lower ends of said pipes, and a pipe open at one end to the atmosphere and connected at its other end to said chamber above said openings for supplying air to the chamber and thereby to said pipes through said openings when the latter are uncovered during flushing.

13. In a flushing-cistern, a siphon, a plurality of pipes connected at their upper ends to said siphon and having openings in their lower ends exposed to the rising and falling action of the body of the flushing-liquid but above the level of the influx of said siphon, each of said pipes having a bore of relatively small diameter and having an ever-open air-inlet above the normal water-level, a chamber in communication with the cistern and receiving the lower ends of said pipes, and a pipe open at one end to the atmosphere and connected at its other end to said chamber above the said openings for

supplying air to the chamber and thereby to said pipes through said openings when the latter are uncovered during flushing.

14. In a flushing cistern, a siphon, a plurality of pipes connected at their upper ends to said siphon and having openings in their lower ends exposed to the rising and falling action of the body of the flushing-liquid but above the level of the influx of said siphon, a chamber in communication with the cistern and receiving the lower ends of said pipes, a pipe open at one end to the atmosphere and connected at its other end to said chamber for supplying air thereto and thereby to said pipes through said openings when the latter are uncovered during flushing, and a silencing-device at the inlet end of the air-supplying pipe.

15. In a flushing-cistern, a bell constituting the short leg of a siphon, a chamber in proximity to the inlet-edge of said bell and in communication with the cistern, a pipe connected at one end to the top of said bell and at its other end to said chamber, the chamber-opening of said pipe being exposed to the rising and falling action of the body of the flushing-liquid but above the level of the inlet to said bell, and a pipe open at one end to the atmosphere and connected at its other end to said chamber for supplying air thereto and thereby to the first pipe through said opening when the latter is uncovered during flushing.

16. In a flushing-cistern, a bell constituting the short leg of a siphon, a chamber in proximity to the inlet-edge of said bell and in communication with the cistern, a pipe connected at one end to the top of said bell and at its other end to said chamber, the chamber-opening of said pipe being exposed to the rising and falling action of the body of the flushing-liquid but above the level of the inlet to said bell, said pipe having an ever-open air-inlet above the normal water-level, and a pipe open at one end to the atmosphere and connected at its other end to said chamber for supplying air thereto and thereby to the first pipe through said opening when the latter is uncovered during flushing.

In testimony that I claim the foregoing as my invention, I have signed my name in the presence of the subscribing witnesses this 13th day of May, 1915.

RUDOLPH HENRIK PAUS.
